UNITED STATES PATENT OFFICE.

SURN JACKSON, OF STOCKTON, CALIFORNIA.

PUMP.

SPECIFICATION forming part of Letters Patent No. 270,900, dated January 28, 1883.

Application filed August 12, 1882. (No model.)

To all whom it may concern:

Be it known that I, SURN JACKSON, a citizen of the United States, residing at Stockton, in the county of San Joaquin and State 5 of California, have invented certain new and useful Improvements in Pumps; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 My invention relates particularly to that class of pumps known to the trade as suction and lift (combination) pumps, in which water is raised from wells of various depths by plungers and valves.

20 The object of my invention is to simplify and cheapen and at the same time to render more effective the operation of such pumps.

My invention consists of a novel apparatus for raising the water, which is accomplished 25 by the use of particularly-constructed valves and plungers, in combination with certain other devices, such as will be hereinafter described.

Referring to accompanying drawings, Figure 30 1 is a vertical sectional view of my entire apparatus. Figs. 2, 3, 4, and 5 are detached views of parts of lower valve, Fig. 2 being the top flange, Fig. 3 the clapper, Fig. 4 the bridge having guide for upper end of clapper-stem, and Fig. 5 the bottom flange with lugs 35 and slots, and having guide for lower end of clapper-stem. Figs. 6, 7, 8, and 9 are detached views of my improved plunger, Fig. 6 being section of plunger proper, showing the bolt 40 that secures the bridge to it, Fig. 7 being said bridge; Fig. 8 is clapper, and Fig. 9 is a vertical elevation of the plunger proper. Fig. 10 is a view of an improved clapper which 45 may be used in the place of the one illustrated by Fig. 3, if preferred. Fig. 11 is a side elevation of one of the plungers.

My improved plunger consists of F, the plunger proper, and having f, the guide for lower end of clapper-stem, at its foot; G, the 50 clapper, consisting of a, the stem, and b' and b, respectively, the upper and lower flanges, having the leather packing c between; H, the

bridge, having e, the guide of the upper end of stem a of clapper G; I, the bolt securing the bridge H to its position in plunger proper, F, the 55 head resting in a slot at the top of the forked portion of said plunger proper, F, and the nut upon the head of bridge H, the point of the bolt fitting into a circular opening thereat, so as to admit of the free play of the nut upon 60 the thread of the bolt I. g is leather packing secured to its position over circular foot of plunger F by the ends of the forks of bridge H pressing thereon, and kept tightly to their place by screwing down the nut upon bolt I. 65 The circular foot of plunger F contains the guide f of lower end of stem, a, of clapper G.

My improved lower valve consists of body A, the lower flange, A', having the four lugs carrying bolts securing it to E. B' is the 70 valve-seat, which rises to a suitable height above the body A, which has the slots x made through its flange y for the bolts z to catch in; B, the upper flange; C, the clapper, consisting of flanges b' and b, bolted together, with the 75 leather c between, and stem a, the leather c resting upon seat B'; D, the bridge, the roof of which has a round hole as guide for upper end of stem a of clapper C, the body A having the guide d for the lower end of said stem a. 80

Having described the various parts, I will now set forth the manner of use, together with my method of producing a continuous stream of water.

Any suitable style and size of piping is inserted in the well and secured to the coupling of body A, which is secured to platform E (the coupling of flange A resting in an opening of platform E) by the bolts of the lugs A'. By this method of fastening the body A to the 90 frame E the lower valve and apparatus above mentioned may be removed by removing the bolts z, and thus taking off the body A without disturbing the pipe in the well. The complete clapper C is then placed in position by 95 inserting the lower end of its stem a into guide d of body A. Bridge D is then placed in position, the circular hole in its summit taking the upper end of stem a of clapper C and acting as its guide. B, the upper flange attached to 100 the lower end of a pump-cylinder, is then placed in position, and secured there by bolts passing down through slots of flange A'. My improved plunger as first above described is then in-

serted in the cylinder, and being properly connected with the usual plunger-rod the pump is then ready for operation by the usual method as a single-action pump; but should it be desired to use that portion of my invention as above suggested, by which a continuous stream of water may be raised, another section of cylinder connected to upper end of the first-mentioned cylinder by flanges J (having a bridge,) and J' must be employed and another of my improved plungers placed therein, and the two plungers connected and operated by the following device: The upper plunger has the rod N connected to it, and is operated in the usual manner; but the lower piston is caused to move downward by the combined help of the weight of the water above it and the springs O while the upper piston is being raised upward, and the lower piston is drawn upward as the upper piston descends through the force that is exerted upon it by the pressure of the upper piston on the rod M. This rod M has its upper end forked, so that the upper piston will press squarely upon it, and is guided in its vertical movements by the guide P, which forms a part of or is secured to the flange J. To the lower end of the rod M is secured the cord, wire, or chain L, which passes up over the pulley K, and then has its other end fastened to the upper end of the lower piston. When the upper piston is forced downward, it strikes upon and forces the rod M downward, thereby drawing the lower piston upward through the cord, wire, or chain L. When the upper piston is raised upward, the combined weight of water upon the lower piston and the pull of the coiled springs O draw and force the lower piston downward, thereby forcing the rod M through the cord, wire, or chain L upward.

By this above device and method a continuous stream of water is kept flowing from the nozzle of the upper section of the cylinder whenever the pumping apparatus, as described, is set in operation.

My devices may be applied to an ordinary force-pump by adding the necessary packing and piston at the head of the upper section of cylinder.

In place of the clapper C of the lower valve may be used, if preferred, a clapper, C', as shown in Fig. 10, which consists of a clapper-stem, a',

with top flange, having secured to it by bolts a forked guide, b', with leather c' between it and the flange. This device for a clapper I consider more certain in its operation, being less liable to wear and lose its position.

When it is desired to remove the clapper G from its position in the plunger, the nut of bolt I is loosened on its thread, and thus permits the easy removal of clapper G. When it is desired to change from the double action to the single action, the driving-rod of the upper plunger may be sufficiently shortened, and thus prevent the plunger upon its downward stroke from reaching the head of the propeller M, which will cause lower plunger to lie dormant at the bottom of the lower section of cylinder.

Having thus described my invention, I claim and desire to secure by Letters Patent—

1. The combination of the body A, having the flange A', valve-seat B', and flange y, having the slots x, with the platform E, flange B, bridge D, and valve, the parts being secured together substantially as shown.

2. The combination of plunger F, provided with the guide f, and having a recess in its side to receive the packing g, the bridge H, and bolt I with the valve or clapper, substantially as described.

3. The combination of the upper plunger, a vertically-moving rod, M, a lower piston, and a cord, wire, or chain, which connects the rod and lower piston together, and a guide for the cord, the rod being entirely disconnected from the upper piston, substantially as set forth.

4. The combination of the upper plunger, a vertically-moving rod, a connecting cord, wire, or chain, and a guiding-pulley, the lower piston or plunger, and the springs O, substantially as specified.

5. The combination of the upper plunger, a vertically moving rod, a connecting cord, wire, or chain, a guiding-pulley and a suitable guide therefor, and the lower plunger, substantially as shown.

In testimony whereof I affix my signature in presence of two witnesses.

SURN JACKSON.
